US00D757680S

(12) **United States Design Patent**
Kelly et al.

(10) **Patent No.:** **US D757,680 S**
(b4) **Date of Patent:** **** May 31, 2016**

- (54) **HEADPHONE**
- (71) Applicant: **Skullcandy, Inc.**, Park City, UT (US)
- (72) Inventors: **Peter M. Kelly**, Park City, UT (US);
Randall J. Hull, Park City, UT (US);
David G. Vogt, Jr., Salt Lake City, UT (US)
- (73) Assignee: **Skullcandy, Inc.**, Park City, UT (US)
- (**) Term: **14 Years**
- (21) Appl. No.: **29/513,680**
- (22) Filed: **Jan. 5, 2015**
- (51) LOC (10) Cl. **14-01**
- (52) U.S. Cl. **D14/205**
- (58) **Field of Classification Search**

(57) **CLAIM**

The ornamental design for a headphone, as shown and described.

DESCRIPTION

FIG. 1 is a perspective view of an embodiment of a headphone;

FIG. 2 is a right side view of the headphone shown in FIG. 1;
FIG. 3 is a left side view of the headphone shown in FIG. 1;
FIG. 4 is a back view of the headphone shown in FIG. 1;
FIG. 5 is a front view of the headphone shown in FIG. 1;
FIG. 6 is a top view of the headphone shown in FIG. 1; and,
FIG. 7 is a bottom view of the headphone shown in FIG. 1.
The broken lines in FIGS. 1 through 7 are for environmental purposes only and do not form any part of the claimed design.

1 Claim, 6 Drawing Sheets
